UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF OF NEW YORK.

TWO-WAY-SIGNALING SYSTEM.

Application filed August 7, 1920. Serial No. 401,888.

To all whom it may concern:

Be it known that I, RAYMOND A. HEISING, a citizen of the United States, residing at East Orange, in the county of Essex, State 5 of New Jersey, have invented certain new and useful Improvements in Two-Way-Signaling Systems, of which the following is a full, clear, concise, and exact description.

The present invention relates to two-way 10 signaling circuits. More particularly, the invention relates to two-way transmitting and receiving circuits in which the transmitter and the receiver are both permanently associated with the same circuit, and 15 has for an object the reduction or elimination of the response of the receiver to energy in the local transmitter circuit.

In signaling systems employing modulated waves, it is common to provide a 20 modulator by which the high frequency or carrier waves or currents are controlled in accordance with the signals to be transmitted, and a detector or demodulator for deriving from a received signal-modulated 25 wave, the current component representing the signal to be received. In such systems, balanced circuits are usually provided for making the detector neutral with respect to the modulator so that the high-frequency 30 modulated energy from the output of the modulator does not enter the local detector circuit. In an application of H. W. Nichols, Serial No. 326,493, filed September 26, 1919, a system is disclosed in which a single high- 35 frequency set is used for both modulating and detecting, and this set is connected to the line or to the antenna through a single coupling or tuned circuit or filter, thus dispensing with the high frequency balance. 40 In some cases, however, and more particularly where the ratio of transmitted to received energy is large, the side tone in the receiver of such a system, that is, the response of the receiver to energy in the local 45 transmitter, may be large. This side tone can not be reduced or eliminated by high frequency balancing circuits in a system of this character, since the same element, for example, a discharge device of the usual 50 three element vacuum tube type, serves to act both upon the outgoing high frequency energy and the incoming modulated energy, and the receiver and transmitter are both permanently connected to this element. The

present invention provides a balance 55 between the transmitter and the receiver preferably by controlling currents of the signaling frequencies instead of the modulated high frequencies and is, therefore, particularly applicable to a system of the type indicated in which both the transmitter and receiver are associated with the same high-frequency set.

Although the energy transfer between the transmitter and the local receiver is spoken 60 of as side-tone, it does not necessarily appear as intelligible sound but may give any kind of a response depending upon the type of receiver used, and this term, as used throughout the present specification and as 65 commonly used in the art, is as applicable to a telegraph receiver for instance, as to a telephone receiver.

In the drawing, Fig. 1 illustrates diagrammatically one form of the invention as 70 applied to a radio telephone system, and Fig. 2 shows a somewhat different circuit arrangement embodying the invention in a high frequency wire telephone system.

In Fig. 1, a modulating system of the type 75 commonly known as the constant current modulating system and including an oscillator O and a modulator M, is coupled to the antenna 1 through the power amplifier A. The oscillator itself, comprises a dis- 80 charge tube 2, which may be of the usual construction and has a filament, a grid and a plate connected to different points of the oscillatory circuit comprised of inductances 85 3 and 4, and variable capacity 5. By means 90 of the condenser 5, the period at which the tube oscillates may be controlled at will. The modulator M comprises a discharge tube similar in construction to 2, and space current from the source 6 is supplied to the 95 tubes 2 and 8 in parallel through the high inductance choke coil 7. The inductance of this choke coil is so great that current variations of frequencies of the order of those used in speech are not transmitted 100 through the coil. In the space current path for the tube 8, an additional choke coil 9 is provided having such an inductance as to freely pass currents of voice frequency but to exclude from the circuit of the tube 8 105 currents of the high frequency generated by the oscillator O. The impedance of the tube 8 may be varied in accordance with speech

waves impressed upon the circuit of the grid or impedance control element through the transformer 10 from the speech current circuit 11, which is shown as containing a microphone transmitter T. Changes in the impedance of the tube 8 cause variations in current through the tube from the source 6 and since the large choke coil 7 keeps the total space current supplied to the tubes 2 and 8 in parallel practically constant, a current change is produced in the plate circuit of the tube 2 which is substantially complementary to that produced in the space current of the modulator M. The amplitude of the output wave from the oscillator O is, therefore, varied in accordance with speech.

This particular method of modulating the high frequency wave forms no part of the present invention, which is not dependent upon any particular system of modulation as will appear hereinafter, but for purposes of illustration this system of modulation which is well adapted for use with the present invention has been shown and described.

The modulated output current from the oscillator O is impressed upon the amplifier A, by means of a coil 12 inductively related to the coil 4 of the oscillator. The output circuit of the amplifier is coupled to the antenna 1 by means of the variable inductive coupling 14 and contains a condenser 15 which should be of such a size as to offer negligible impedance to currents of the frequency generated by the oscillator O but to offer high impedance to currents of the voice frequencies or other signaling frequency. The space current for the amplifier A is supplied from the battery 13 through a receiver R, the battery and receiver being connected in shunt to the condenser 15. The action of this much of the circuit is that a certain degree of detection of the modulated high frequency wave takes place in the amplifier A whether the wave is being transmitted to the antenna 1 or is being received from the antenna 1 in the plate circuit of the amplifier. This is probably due to a slight curvature of that portion of the tube characteristic over which the amplifier A operates. The low frequency or signaling component resulting from this detecting action of the amplifier is heard in the receiver R.

In the case of a radio system, the energy transmitted is enormously large compared with the energy received and the sounds heard in the receiver R, due to currents in the transmitter circuit 11, are liable to be very loud. In accordance with the invention, this side tone is reduced or eliminated by means of a neutralizing circuit connected between the circuit 11 and the circuit of the receiver R and including the electron discharge device 16. By means of this current path, energy from the transmitting circuit 11 is transferred directly to the receiver cir-

cuit. By means of the variable coupling 17, the desired amount of current in this circuit can be impressed upon the receiver, and the phase of the impressed current may be made such as to oppose current in the receiver R which results from detection of the transmitted wave in the amplifier A. The main purpose of the discharge device 16 is to prevent the passage of current from the receiver circuit to the transmitting circuit 11 which might, under certain circumstances, produce singing of the system. The discharge device 16 being a uni-laterally conducting element prevents the passage of a signal except in the direction from the transmitting to the receiving circuit. The device 16 may be an amplifier if desired and may be controlled to amplify the currents impressed upon the receiver through the coupling 17. The high frequency waves received from the distant station will be detected by the amplifier A and received in the receiver R without producing any effect upon the neutralizing current path. By properly adjusting the constants of the current path and the phases of the currents, the signal heard in the receiver when a message is being transmitted from the local station may be made to have substantially the same degree of loudness as the received signals, or the side tone may be eliminated altogether if desired.

In Fig. 2 is shown diagrammatically, a complete two-way circuit arrangement at station S on the high frequency telephone line L. The oscillator O' is of a well-known type and has its frequency controlled by a variable condenser 5 as in the case of the previously described oscillator circuit. The oscillator is coupled, by means of the coil 4, to the input circuit of a three-element modulating tube M' and speech waves from the circuit 11' are, at the same time, impressed upon the input circuit of the modulator through the coupling 10'. For receiving the outgoing and the incoming signals, the receiver R is connected to the output circuit of the modulator. In this case, no amplifier for the modulated waves is shown but it is obvious that an amplifier may be used and in practice probably would be desirable, in which case the receiver R would be connected to the output circuit of the amplifier as in the case of Fig. 1. A neutralizing circuit including the discharge device 16 is provided, as before, between the transmitting circuit 11' and the receiving circuit. The frequency of the carrier wave used in the circuit of Fig. 2, is presumed to be lower than the carrier frequency used in Fig. 1 although no definite relation need exist between the frequencies used in the radio system and those used on the line. If the carrier wave is only slightly above the upper limits of audibility, the modulated wave may comprise a frequency range representing a con-

siderable percentage of the carrier-wave frequency itself, and for the purpose of transmitting all of the frequencies comprised in such a wave, a band filter F is shown for associating the transmitting and receiving set with the line L. The operation of the system of Fig. 2 is substantially the same as that of the circuit of Fig. 1. Other stations, similar to that shown at S, may be provided 10 on the line L and each pair of stations would, as is well understood, employ different carrier wave frequencies. A tap connection for another station, S', is indicated in the drawing.

15 Although the invention has been illustrated and described as embodied in a telephone system, it is evident that it is clearly applicable to other types of signaling or of transmission in which the response of a receiver to energy in the transmitting circuit is to be reduced or eliminated. The scope 20 of the invention is defined in the following claims.

What is claimed is:

25 1. In a two-way modulated wave signaling system, a repeating device for transmitting a high frequency wave modulated in accordance with signaling-frequency currents and for translating modulations 30 of a high frequency wave into signaling currents, a transmitter and a receiver for signaling frequency currents associated with said repeating device, and means for reducing the effect on said receiver of currents of signaling frequency in said transmitter comprising a circuit between said transmitter and receiver for impressing signaling currents from said transmitter upon 35 said receiver.

40 2. In a two-way signaling system employing modulated waves of ultra-audible frequency, a common electric discharge tube circuit for translating currents of audible frequency into variations of ultra-audible 45 frequency and vice versa, a transmitter and a receiver for currents of audible frequency associated with said circuit, and means for reducing the effect in said receiver of current in said transmitter impressed through 50 the medium of said circuit comprising a 55 neutralizing path for transmitting current of audible frequency from said transmitter to said receiver of such phase as to oppose the current in said receiver impressed through the medium of said circuit.

3. In a two-way system, a discharge device, a transmitting means for impressing high frequency waves upon said device for transmission, means for impressing received 60 high-frequency waves upon said device for detection, a receiver associated with said device for receiving the detected signal component of the received wave, and means for reducing the effect on said receiver of currents impressed upon said device for trans-

mission comprising a circuit independent of said discharge device for transmitting neutralizing current from said transmitting means to said receiver.

4. In a two-way signaling system, a circuit 70 for supplying high-frequency modulated waves for transmission, including a discharge device and a circuit for impressing energy thereupon including a telephone transmitter, said discharge device acting to transmit 75 high-frequency waves and to detect both transmitted and received high frequency waves, a telephone receiver associated with the output circuit of said discharge device for receiving the detected component of the 80 high-frequency waves, and means for reducing the side-tone in said telephone receiver comprising a circuit, connected between said transmitter and said receiver, for supplying to said receiver currents substantially opposite in phase to the currents impressed upon said receiver from said transmitter through said device.

5. In a two-way signaling system, a circuit 85 for supplying high-frequency modulated waves for transmission, including a discharge device and a circuit for impressing energy thereupon including a telephone transmitter, said discharge device acting to transmit high-frequency waves and to detect 90 both transmitted and received high-frequency waves, a telephone receiver associated with the output circuit of said discharge device for receiving the detected component of the high-frequency waves, and means for 95 reducing the side-tone in said telephone receiver comprising a circuit, connected between said transmitter and said receiver, for supplying to said receiver currents substantially opposite in phase to the currents impressed upon said receiver from said transmitter through said device, said last mentioned circuit comprising a discharge device 100 for permitting current to pass only in one direction between said transmitter and said receiver.

6. In a signaling system, a common transmitting and receiving electric discharge tube, a transmitter for impressing current upon said tube and a receiver for receiving current of the same order of frequency from said tube, a connection between said transmitter and said receiver for neutralizing at least partially the effect in said receiver of current impressed on said tube from said transmitter and means for preventing the system from singing comprising a uni-laterally conducting element in said connection.

7. In a two-way modulated wave signaling system, a wave repeater for transmitting and receiving modulated waves, a signaling-frequency transmitter and a signaling-frequency receiver associated with said wave repeater, and a uni-laterally conducting circuit between said transmitter and said re- 120 125

- ceiver for transmitting energy from said transmitter to said receiver.
8. A modulated wave signaling system comprising means including a transmitting instrument and a vacuum tube for producing and modulating a carrier wave for signal transmission, means including a receiving instrument and said vacuum tube for detecting a modulated carrier wave for signal reception, and means controlled by said transmitting instrument for reducing the side-tone in said receiving instrument without affecting the responsiveness of said receiving instrument or its circuits to signaling waves received from distant stations.
9. In combination, an electric discharge tube having a cathode, an anode and a control element, means to cause said tube to transmit a speech-modulated high frequency wave, a microphone circuit associated with said tube, a telephone receiver associated with said tube for receiving the speech frequency component of modulated waves present in the circuit of said tube, and an anti-side tone circuit between said microphone circuit and said receiver circuit for reducing the loudness of sounds produced in said receiver.
10. In combination, an electric discharge tube having a cathode, an anode and a control element, means to cause said tube to transmit a speech modulated high frequency wave, a microphone circuit associated with said tube, a telephone receiver associated

with said tube for receiving the speech frequency component of modulated waves present in the circuit of said tube, an anti-side tone circuit between said microphone circuit and said receiver circuit, and means permitting said anti-side tone circuit to transmit current variations in only one direction.

11. In a two-way signaling system, an electric discharge tube having a cathode, an anode and a control element, a transmission circuit, a telephone transmitter and a telephone receiver, said tube being arranged with respect to the other mentioned elements to impress a high frequency wave on said transmission circuit modulated in accordance with speech waves from said telephone transmitter, and to receive from said transmission circuit speech modulated high frequency waves and to impress on said receiver the speech component of the received modulated waves and also speech waves from said telephone transmitter, and a circuit for reducing the amplitude of the speech currents in said receiver originating in said telephone transmitter, said circuit comprising a connection between said telephone transmitter and said receiver containing means for permitting current transmission only in the direction from said transmitter to said receiver.

In witness whereof, I hereto subscribe my name this 4th day of August A. D., 1920.

RAYMOND A. HEISING.
